CLAIM

The ornamental design for a male charging port connector as shown and described.

DESCRIPTION

FIG. 1 is front perspective view of a male charging port connector;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown depict the portions of the male charging port connector that form no part of the claimed design.

1 Claim, 6 Drawing Sheets
